(57) **CLAIM**

I claim the ornamental design for automated external defibrillator wall mount, as shown and described.

DESCRIPTION

FIG. 1 is a front corner perspective view of an automated external defibrillator wall mount according to an embodiment of the invention in the form of an automated external defibrillator wall mount rack. The view from the adjacent front corner being a mirror image thereof.

FIG. 2 is a front elevational view of an automated external defibrillator wall mount according to an embodiment of the invention.

FIG. 3 is a rear elevational view of an automated external defibrillator wall mount according to an embodiment of the invention.

FIG. 4 is a right side elevational view of an automated external defibrillator wall mount according to an embodiment of the invention.

FIG. 5 is a left side elevational view of an automated external defibrillator wall mount according to an embodiment of the invention.

FIG. 6 is a top plan view of an automated external defibrillator wall mount according to an embodiment of the invention; and,

FIG. 7 is a bottom view of an automated external defibrillator wall mount according to an embodiment of the invention.
